UNITED STATES PATENT OFFICE.

GEORGE CARTWRIGHT, OF PATERSON, NEW JERSEY, ASSIGNOR OF ONE-HALF TO
WILLIAM WRIGHT, OF PATERSON, NEW JERSEY.

DIVIDED NUT.

964,752.

Specification of Letters Patent. Patented July 19, 1910.

Original application filed June 1, 1909, Serial No. 499,496. Divided and this application filed February 2, 1910. Serial No. 541,507.

To all whom it may concern:

Be it known that I, GEORGE CARTWRIGHT, citizen of the United States of America, residing at 214 17th avenue, Paterson, New Jersey, in the county of Passaic and State of New Jersey, have invented certain new and useful Improvements in Divided Nuts, of which the following is a specification.

My invention relates to an improved form of divided nut, acting in the nature of a jaw clutch, and embodies means whereby the jaws thereof may be caused to quickly and positively engage and become disengaged from a spindle or other support.

The present application is a division of my copending application for Letters Patent, Serial Number 499,496, filed June 1st, 1909.

In the accompanying drawing wherein one embodiment of my invention is illustrated, Figure 1 is an end view of my improved form of divided nut, illustrating the same in operative position; Fig. 2 is a top plan view thereof; Fig. 3 is a vertical sectional view thereof; and Fig. 4 is a bottom plan view thereof.

Referring to the drawing in detail, the divided nut as there shown comprises a substantially rectangular plate 10 and the angular side members 11 and 12 designed to engage and travel on a suitable support, such as the shaft 13. As will be noted from Figs. 2 and 3 the plate 10 is provided with an elongated slot 14 designed to receive the bases 15 and 16 of the semicircular jaws 17 and 18, the connection between the bases 15 and 16 and plate 10 being in the nature of a mortise and tenon joint. The lower face of each base is provided with an eccentric curved slot 19 designed to receive pins 20 arranged at diametrically opposite points upon a circular plate 21 (revolvable in an undercut part of the plate 10) formed rigidly with a short shaft 22 upon which the sleeve 23 of an operating crank handle 24 is secured.

When the crank handle is parallel to the spindle 13 the pins 20 rest in the lower ends X of the slots 19 and the jaws 17 and 18 of the nut are closed and embrace the screw spindle 13. When the crank handle is moved, by mechanism to be hereinafter described, to a position perpendicular to the spindle 13 the pins 20 are moved to the op-

posite end Y of the slots 19, and compression springs 25, arranged in slots 26 in the jaw members, extend and force the jaw members apart causing them to release engagement with the spindle 13.

Provided upon the forward face of the plate 10 is a spring pressed latch 27 (Figs. 1 and 2) having a projecting end 28 designed to engage a lug 29 formed upon the inner face of the crank handle 24. The divided nut is provided with a depending arm such as 30 which is adapted, when the nut moves along the spindle 13, to move along a second spindle 31, a disk or sleeve 32, which is prevented from turning on the spindle by the key 31^a entering a slot in the disk. Pivoted to the depending arm 30 is a pawl having one arm 33 extending into a semi-circular slot 34 on the lower face of the latch 27 and the other arm 35 projecting into the path of a cam 36 formed on a collar 37 designed to be secured, by means of set screw 38, to the spindle 13. It will be understood that when the cam nose 36 revolves and strikes the arm 35 of the pawl, the other arm 33 will draw the latch out of engagement with the lug 29 permitting the springs 25 to extend and cause the pins 20 to travel in the slots 19 thus permitting the jaws to open.

Following is a brief description of the operation of the entire mechanism:—Assuming the several parts to occupy the positions shown in Fig. 1, and power applied to cause spindle 13 to revolve, the latter will cause the divided nut to be fed along the spindle. The depending arm 30 will move the friction disk 32 longitudinally on the shaft 31. When the divided nut reaches the point of the spindle 13 where the collar 37 is secured, the cam 36 of the latter will strike pawl arm 35 causing release of the latch 27 from the lug 29 and thus permitting the springs 25 to extend and force the jaws 17 and 18 apart, in doing which the plate 21 is revolved and the pins 20 move from ends X to ends Y in the slots 19 and the crank handle is turned to a position perpendicular to the spindle 13. The jaws are then opened and out of engagement with the spindle 13 and no further movement of the divided nut or of the disk 32 occurs. When it is desired to reengage the jaws with the spindle 13 the crank handle 24 is turned, causing the plate 21 to revolve

and the pins 20 to ride in the slots 19 back to the position X thus bringing the jaws together about the spindle, and when the latch 27 is again in engagement with the lug 29 5 the parts are locked in position and remain so until the cam 36 is again encountered by the pawl arm 35.

While in the foregoing specification I have described my invention in detail, I desire 10 it to be understood that I do not limit myself to such details but what I claim as new and desire to secure by Letters Patent is:—

1. In a divided nut, the combination with a pair of jaws having their bases slotted, of 15 pins traveling in the slots designed to close the jaws, and springs within the jaws for forcing the same apart.

2. In a device of the character described, the combination with a pair of jaws the 20 bases of which are provided with eccentric slots, of springs within the jaws for forcing the same apart, pins projecting into and adapted to travel in said slots, and means for causing the pins to travel in the slots to 25 force the jaws together.

3. In a device of the character described, the combination with a pair of jaws having their bases slotted, of springs within the jaws for forcing the same apart, a rotary

plate, pins carried thereby and projecting into the slotted bases, and a crank handle for rotating said plate to cause the pins to travel in the slots and close the jaws.

4. In a device of the character described, the combination with a hanger frame, of a pair of jaws carried thereby, a latch carried by the hanger frame, a pawl engaging the latch and means adapted to contact with said pawl to thereby release the latch and open said jaws.

5. In a device of the character described, the combination with a hanger frame, of a pair of jaws carried thereby, a support adapted to be engaged by the jaws, a crank handle for closing said jaws, said handle having a lug, a latch having a portion projecting into engagement with said lug, a pawl engaging said latch and a cam secured to said support and designed to operate said pawl to release the catch from the lug and permit the jaws to be disengaged from the support.

In testimony whereof I have affixed my signature in presence of two witnesses:

GEORGE CARTWRIGHT.

Witnesses:

OTTO MARK,

C. CAUSIA FRANCK.
